UNITED STATES PATENT OFFICE.

GEORGE L. HALL, OF NEW YORK, N. Y., ASSIGNOR TO THE NATIONAL RAILWAY MATERIALS COMPANY, OF NEW YORK, N. Y., A CORPORATION OF NEW YORK.

THREE-TIE STEP-UP RAIL-JOINT.

No. 890,422.

Specification of Letters Patent.

Patented June 9, 1908.

Application filed December 21, 1906. Serial No. 348,854.

To all whom it may concern:

Be it known that I, GEORGE L. HALL, a citizen of the United States, residing in the borough of Manhattan, city, county, and 5 State of New York, have invented certain new and useful Improvements in Three-Tie Step-Up Rail-Joints, of which the following is a specification, reference being had therein to the accompanying drawings, in which—
10 Figure 1 is a side elevation of the meeting ends of two railroad rails showing the joint in position; Fig. 2 a transverse sectional view on the line II—II of Fig. 1; Fig. 3 a similar view on the line III—III of Fig. 1; Fig. 4 a 15 detail perspective view of one of the splice bars; Fig. 5 a side elevation of the inner side of one of the splice bars in position on three ties, a portion of the base support being corrugated; Fig. 6 a detail view of one splice 20 bar provided with a base support adapted to be extended entirely across the base of the rail; Figs. 7 & 8 are cross-sectional views showing slightly different forms of stiffening webs for the splice bars; Fig. 9 a detail bottom plan view of a pair of splice bars showing 25 another form of base support.

One of the objects of this invention is to provide a step-up rail joint with a base support midway its ends and projecting under 30 the adjoining ends of connected rails, said base support terminating short of the ends of the splice bars.

A further object of the invention is to provide a three-tie step-up joint, that is to say, a 35 joint adapted to be supported on three ties, the joint between the rails being directly over one of the ties.

Another object of the invention is to provide a step-up joint which will also serve as 40 an anti-creeping device to prevent the creeping of the railroad rails and to hold the ties straight, that is to say, perpendicular with respect to the railroad rails.

Other objects of the invention relating 45 more particularly to details of construction will appear hereinafter.

The joint is composed of two members or splice bars 1 and 2, each of which consists of a web 3 provided at its upper edge with the 50 inwardly and downwardly inclined bearing face 4 to support the head of the larger rail. This web, from a point midway the ends of the splice bar to one end thereof, is enlarged vertically or stepped-up to form the enlarged 55 part 5 of the web, said enlarged portion being

provided at its upper edge with the downward inclined bearing face 6 to support the head of the smaller rail. At the lower edge of this vertical web and integral therewith is formed the outwardly and downwardly inclined flange 7 which is adapted to rest upon the base of the rails.

At a point midway the ends of the splice bar and integral with the flange 7, is formed an inward extending web 8 which stiffens 65 the bar and forms a base support. This web 8, if found desirable, may be extended in any desired direction below the base of the rail, but it will, of course, be understood that if it be extended, as shown in Fig. 7, or in any 70 similar manner, it will not form a base support, but will merely serve as a stiffening web. In most cases, however, said web will be extended below the lower edge of the flange 7, and is preferably of such length that 75 its ends will abut against the sides of the ties and form an anti-creeping device. As shown in the drawings, said web is of such length that its ends abut against the ends of the ties 8^a and 8^b, the middle part of said web 80 resting upon an intermediate tie 8^c thus forming an anti-creeping device and preventing the creeping of the rails. The portion of the base support 9, directly under the web 3, is considerably thinner than the 85 portion 10, extending under the web 5, that portion extending under web 5 being adapted to support the lighter rail and to hold it in position to bring its upper surface on a level with the upper surface of the heavier rail 90 supported by the thinner base support.

The ends of the splice bars are formed without base supports, as shown clearly in Fig. 4. That portion of the flange 7, beyond the ends of the base support, is adapted to 95 rest upon the ties, as shown clearly in Figs. 1 and 5. In order to stiffen the web or base support 8, the inner edge thereof may be provided with a longitudinal rib or enlargement 11, as shown in Figs. 2 and 4, said rib 100 extending the full length of the base support and materially stiffening it and the splice bar as a whole. It will be readily manifest that the base supports may be transversely, or longitudinally, corrugated in order to 105 stiffen them, and to save metal as shown at 8^d in Fig. 5. It will, of course, be understood that the base support may be made entirely on one splice bar if desired, as indicated at 8^e in Fig. 6, the other member of 110

the joint being merely an angle-iron having one portion enlarged to support the smaller rail.

In Fig. 9 the base support is formed with the very narrow part 8^g under one rail end, and with the part 8^h almost as broad as the base of the rail, this broader part being adapted to extend under the other rail and to support the same, so that under each rail end there will be a narrow portion of the base support extending inward from one splice bar and a broad base support extending in from the opposite splice bar. If desired, when the base support is in this form it will be provided along its longitudinal edge with a stiffening enlargement or bead.

Whenever it may be necessary to place the smaller rail slightly out of line with the vertical center of the larger rail in order to bring the flange side of the head in line with and flush with the flange side of the larger rail, the stepped-up part of the splice bar will be enlarged laterally sufficiently to properly space the smaller rail. In Fig. 4 the stepped-up portion of the splice bar is shown as thus enlarged at 5^a.

Having thus described my invention, what I claim as new and desire to secure by Letters Patent, is:—

30 1. A step-up rail joint comprising two splice bars, each consisting of a longitudinal vertical web formed at its upper edge with a rail head supporting surface, said web being vertically enlarged for a portion of its length to support the head of the smaller rail, each of said bars being formed at the lower edge of the web with an outward and downward extending flange adapted to fit over the base of the rails, and a base support formed integral with the outer edge of said flange of one of the splice bars at the middle thereof and shorter than the splice bars, that portion of the base support below the enlarged part of the web being corrugated and extending back under the flange and the web and adapted to fit under the rail, the upper surface of said base support below the enlarged portion of the web being higher than the other part thereof, whereby the base of the smaller rail is raised above the base of the larger rail.

2. A step-up joint comprising two splice bars each consisting of a longitudinal vertical web formed at its upper edge with a rail head supporting surface, said web being enlarged for a portion of its length to support the head of the smaller rail, each of said bars being formed at the lower edge of the web with an outward and downward extending flange adapted to fit over the base of the rails, and a base support formed integral with the outer edge of said flange and extending back under the flange and the web and adapted to fit under the rail, said base support being of equal thickness throughout and corrugated to form rail supports of different heights.

3. A step-up joint comprising two splice bars each consisting of a longitudinal vertical web formed at its upper edge with a rail head supporting surface, said web being enlarged for a portion of its length to support the head of the small rail, each of said bars being formed at the lower edge of the web with an outward and downward extending flange adapted to fit over the base of the rails, and a base support formed integral with the outer edge of said flange and extending back under the flange and the web and adapted to fit under the rail, said base support being corrugated to form rail supports of different heights, and terminating short of the ends of the flange to adapt it to engage the ties and serve as an anti-creeping device.

4. A splice bar for step-up rail joints comprising a longitudinal vertical web formed at its upper edge with a rail head supporting surface, said web being enlarged for a portion of its length to support the head of the smaller rail, said bar being formed at the lower edge of the web with an outward and downward extending flange adapted to fit over the base of the rails, and a base support integral with the outer edge of said flange extending back under the flange and the vertical web, and adapted to fit under the rails, said base support being corrugated to form rail supports of different heights.

5. A splice bar for step-up rail joints comprising a longitudinal vertical web formed at its upper edge with a rail head supporting surface, said web being enlarged for a portion of its length to support the head of the smaller rail, said bar being formed at the lower edge of the web with an outward and downward extending flange adapted to fit over the base of the rails, and a base support formed integral with the outer edge of said flange and extending back under the flange and the vertical web and adapted to fit under the rail, said base support being of uniform thickness of metal throughout and corrugated to form rail supports of different heights and terminating short of the ends of the flange to adapt it to engage the ties and serve as an anti-creeping device.

6. A splice bar or connecting plate for railway rail joints comprising a vertical longitudinal rail supporting web adapted along its upper edge to fit under and support the head of the adjoining rails, an outwardly and downwardly inclined flange formed integral with the lower edge of said web and adapted to fit over the base of the rail, and an inward turned base support formed integral with the free edge of said flange and extending under the flange and the web and adapted to extend under and support the abutting ends of the rails to be connected, a portion of said base support being in width substantially equal to the width of the base of the rail, the remainder of said base support being very

narrow and being adapted to extend only slightly under the base of the rail, said broad and narrow portions of the base support being connected together substantially midway between the ends of the splice bar.

7. A step - up rail joint comprising two splice bars each of which is formed with a vertical longitudinal supporting web adapted to support the heads of the rails, a portion of 10 said web being stepped-up vertically to support the smaller rail, an outwardly and downwardly inclined flange formed at the base of said web, said flange being equal in length to the web and adapted at its ends to rest on the 15 ties, and a short stiffening web and base support formed integral with the free edge of the flange and extending across the line of the 20 enlargement of the web, the upper surface of said base support being of different heights to support the rails and terminating short of the ends of the flange, the web for supporting one rail being narrower than the web supporting the other rail.

8. A step - up rail joint comprising two splice bars each of which is formed with a

vertical longitudinal supporting web adapted to support the heads of the rails, a portion of 25 said web being stepped-up vertically to support the smaller rail, an outwardly and downwardly inclined flange formed at the base of said web, said flange being equal in length to the web and adapted at its ends to rest on the 30 ties, and a short stiffening web and base support formed integral with the free edge of the flange and extending across the line of enlargement of the web, the upper surface of 35 said base support being of different heights to support the rails and terminating short of the ends of the flange, the web for supporting one rail being narrower than the web supporting the other rail.

In testimony whereof I hereunto affix my 40 signature in the presence of two witnesses this 20th day of December 1906.
